HAND RAILING BRACKET OR SIMILAR ARTICLE

Robert S. Van Riper, Ridgewood, N.J.
(109 Bergen Turnpike, Little Ferry, N.J.)

Filed Jan. 31, 1964, Ser. No. 78,448

Term of patent 14 years

(Cl. D13—7)

FIG. 1.

FIG. 2.

FIG. 3.

FIGURE 1 is a perspective view of my novel design for a hand railing bracket or similar article;

I claim:

The ornamental design for a hand railing bracket or similar article, substantially as shown.
